UNITED STATES PATENT OFFICE

JAN STRENG, OF NEW YORK, N. Y., ASSIGNOR TO KOLSTER RADIO, INC., OF NEW YORK,
N. Y., A CORPORATION OF NEW YORK

DESIGN FOR A RADIOCABINET

Application filed September 25, 1931. Serial No. 41,220. Term of patent 3½ years.

To all whom it may concern:

Be it known that I, JAN STRENG, a citizen of the United States, and a resident of New York, in the county of New York and State of New York, have invented a new, original, and ornamental Design for Radiocabinets, of which the following is a specification, reference being had to the accompanying drawings, forming a part thereof.

Fig. 1 shows a front perspective view of the radiocabinet.

Fig. 2 shows a top view of the radiocabinet

partially broken away for convenience of illustration.

The sides of the radiocabinet each have a plain panel formed by the corner mouldings and the extensions of the top and base portions shown in Fig. 1.

I claim:

The ornamental design for a radiocabinet, as shown and described.

In witness whereof, I hereunto subscribe my name this 11 day of Sept. 1931.

JAN STRENG.
